Thomas E. Coggeshall. The Schedule, referred to in the Letters Patent annexed being part of the same, containing a description, in the words of the said Thomas Coggeshall himself, of his improvement in the safety valve for Steam Engines, Boilers, &c., annexed to the Hydrostatic safety valve.

To all whom it may concern: be it known that I Thomas Coggeshall, of the city of New York, have invented a new safety valve for the boiler of Steam Engines, which I denominate the Hydrostatic safety valve, and that the following is a full and exact description thereof. The form of my safety valve may be the same as that ordinarily used, namely a truncated cone; instead however of being pressed downwards in the usual way, it is pressed upwards by the weight of a column of water, mercury or other fluid. In the accompanying drawings, those parts which are similar in the different figures, are represented by the same letters. Figure 1. represents a section of the valve by means of which the hydrostatic pressure is made. A is a cylindrical vessel which may be open at top but is closed at bottom. This is placed within a drum B, which is to contain water or other fluid, by which the pressure is to be made. It is evident that when the vessel A is placed within the drum B and water is forced into the cavity between them, A will be pressed upwards, with a force proportioned to the area of the bottom of A, & the altitude of the fluid in the cavity. C is a shallow vessel in which D stands and is intended to receive any fluid which may escape from B. D, E, H are cocks placed in B to regulate the height of the fluid, and consequently to graduate the pressure, say to 50, 100, 200, and 300 to the square inch. G is a disk of wood or other light material, intended to stiffen the bottom of A and which may also serve to receive the lower end of the valve in, each end of which passes into cavities without the use of joints, as ordinarily made. Fig. 2. is a section of the valve in action. H H is a tube one or both ends of which open into the boiler at I. The inverted cone part is seen at J in the upper part of this tube. K K are ledges to support the hydrostatic apparatus over the boiler, a piece of plank or other like conductor is usually first placed upon the ledges. The valve to is ditched deeply in its lower side to receive the rod M, the lower end of which rests on G. Fig. 3. is a perspective view of the whole apparatus, the graduation by means of which is being explained by figures. A is the drum containing off

finer downwards, I usually place a cover over the head to be shown at Fig. 2, a hole left in the centre of this cover allows the rod to pass through, and a collar Q, formed upon the rod, may cover the hole. Fig. 3 represents another with usual partition, this section shows two holes drilled thro' the valve at P.P. I intend sometimes to drill a number of such holes, to prevent a lesion that adhesion which is known to men of science as having been described by Mr. Clement. The same provision is shown at Fig. 4. There, holes I intend in some instances to connect together, by turning grooves in the face of the valve, removing a portion of metal between them. By this arrangement here described the danger which arises from over-tightening the safety valve, is entirely obviated, or made so difficult and improbable of attempt, as to afford complete security on this score. I have thus given particular exemplification of the principle upon which my improved valve operates, not however intending to confine myself to the precise arrangement herein set forth, as this may be varied by modification, whilst the general principle remains unchanged. What I claim as my invention, is the employing of hydrostatic pressure to close the safety valve; the using the valve in the inverted position; the passing the ends of the valve rod into cavities prepared to receive them without the use of joints; and the drilling of holes thro' the valve as above described, in order to prevent adhesion - or gross or instead.
